DESIGN FOR A HANDLE BAR

John R. Morgan, Oak Park, Ill., assignor to Sears, Roebuck and Co., Chicago, Ill., a corporation of New York

Application July 13, 1940, Serial No. 93,608

Term of patent 7 years

To all whom it may concern:

Be it known that I, John R. Morgan, a citizen of the United States of America, residing at Oak Park, in the county of Cook and State of Illinois, have invented a new, original, and ornamental Design for a Handle Bar, of which the following is a specification, reference being had to the accompanying drawing, forming a part thereof.

I claim:

The ornamental design for a handle bar, substantially as shown.

JOHN R. MORGAN.
